UNITED STATES PATENT OFFICE.

WILLIAM M. REED AND CHESTER P. HEGAN, OF LOUISVILLE, KENTUCKY, ASSIGNORS
TO REED AIR FILTER COMPANY, OF LOUISVILLE, KENTUCKY, A CORPORATION OF
KENTUCKY.

AIR FILTER.

Application filed March 3, 1926 Serial No. 91,860.

This invention relates to air filters and pertains more particularly to a gasket for preventing leakage of air between a filter cell and a surrounding framework.

5 In many types of air filters it is customary practice to provide a supporting framework carrying one or more cells filled with filtering media, which cells are removable from the supporting framework in order that they 10 may be cleaned of accumulated dust and dirt from time to time. Leakage of air between the filter cell and the framework sometimes permits the passage of dust or dirt into the current of filtered air and, accordingly, it is 15 desirable to reduce this leakage to a minimum. It is an object of this invention to provide means to prevent such air leakage, such means comprising, in the preferred embodiment illustrated, a gasket arranged to fill the interstices between the filter cell and frame.

It is a further object of the invention to provide a gasket which shall be simple and inexpensive to construct, but which shall be 25 durable under varying conditions.

A preferred embodiment of the invention is illustrated in the accompanying drawings, in which,

Figure 1 is a front elevation of a filter 30 cell, part of the cell being broken away to better illustrate the location of the gasket.

Figure 2 is a side elevation also broken away, and

Figure 3 is an enlarged sectional view taken 35 on the line 3—3 of Figure 1.

Referring to the drawings, the filter cell 1 is supported in a framework 2 which may surround the entire outer periphery of the cell. The framework 2 may conveniently be 40 formed of channel bars welded or otherwise secured at the corners, said channel bars providing the flanges 3 which lie against the flange 4 of the filter cell when the cell is in operative position.

45 The channel bars also provide the flanges 5 at the rear of the cell which extend in close proximity to the side faces of the cell but which leave an appreciable space therebetween.

50 In order to fill this space and thus prevent leakage of air between the filter cell and the frame, it is proposed to provide gaskets 6 arranged in position to pack the space be-

tween the cell and frame. These gaskets may be secured to all four sides of the frame and 55 may consist of a strip of felt of a width sufficient to provide a flexible edge 7 which lies between the cell and frame.

As illustrated in the accompanying drawings, the gasket may be conveniently fastened to the flange 5 of the frame. As a convenient means of attaching the gasket to the frame, the inner edge of the felt strip may be clamped in a metal channel 8 having a series of apertures therein through which it may 60 be secured to the frame by means of rivets 9. Preferably the channels are somewhat shorter than the felt strips in order that the strips may be flexible at the corners to permit them 65 to flex as the cell is inserted in the frame. 70

In setting up the filter, the frame with the gaskets attached may first be placed in position, after which the filter cell may be inserted therein. As will be observed, the depth of the cell is somewhat greater than 75 the depth of the framework. Accordingly, as the cell is inserted, the rear of the cell is caused to protrude through the framework and the free edges of the gaskets are forced outwardly to form a tight packing between 80 the cell and frame.

It will be understood that the invention may be variously modified and embodied within the scope of the subjoined claims.

We claim as our invention:

1. In an air filter comprising a unit filter cell and surrounding frame, a gasket adapted to prevent leakage between said cell and its surrounding frame, said gasket comprising a strip of flexible material having a substantial 90 portion of its area rigidly secured to said frame, but having an edge free to flex between said frame and cell.

2. In an air filter comprising a unit filter cell and surrounding frame, a gasket adapted 95 to prevent leakage between said cell and its surrounding frame, said gasket comprising a strip of flexible material having a substantial portion of its area and one of its edges bound in a metal channel, but having an edge free to flex between said frame and cell, said gasket being riveted to said frame.

3. A gasket for air filters comprising, a strip of flexible material, a metal channel surrounding one edge of said strip, but leaving the other edge free to flex, said channel 105

and strip being provided with rivet holes through which the gasket may be secured to a supporting member.

4. A gasket for air filters comprising, a strip of flexible material, a metal channel surrounding one edge of said strip, but leaving the other edge free to flex, said channel being of a length less than the length of said strip, said channel and strip being pro-

vided with rivet holes through which the 10 gasket may be secured to a supporting member.

In testimony whereof, we have signed our names to this specification this 19th day of February, 1926.

WILLIAM M. REED.
CHESTER P. HEGAN.
